Primary Examiner — Freda S Nunn(74) *Attorney, Agent, or Firm* — Polsinelli PC(57) **CLAIM**

The ornamental design for a beverage bottle, as shown and described.

DESCRIPTION

FIG. 1 is a perspective view of the beverage bottle.
FIG. 2 is a front elevation view of the beverage bottle.
FIG. 3 is a rear elevation view of the beverage bottle.
FIG. 4 is a right side elevation view of the beverage bottle.
A left side elevation view is a mirror image of the right side elevation view of the beverage bottle.
FIG. 5 is a top plan view of the beverage bottle.
FIG. 6 is a bottom plan view of the beverage bottle; and,
FIG. 7 is another perspective view thereof with the lid of the beverage bottle shown in an open position.
